San Francisco, Calif.

Application December 26, 1939, Serial No. 310,920

7 Claims. (Cl. 5—334)

This invention, a comforter, is designed to overcome the many disadvantages of conventional types of comforters, such as non-adaptability to cover changes or convenient cleaning, and the tendency for the comforters to creep off the bed.

The conventional types of comforters have a covering material which is usually directly filled with an insulating or filling material, such as down, kapok, wool or cotton, and which is customarily quilted or knotted to retain the filling material in a fairly uniform condition of distribution. This type of comforter can only be cleaned by dry methods which are detrimental particularly to wool or down filling material which loses its elasticity and consequent fluffiness through association with the cleaning fluids, and which obviously reduces the insulating efficiency of the filling material.

If a new cover is desired, complete destruction of the comforter is necessary, the filling material must be reconditioned, such as by carding the wool when used, since the filling material has been held in place through the medium of the quilting or knotting employed and which maintains certain portions of the filling material in a compressed state which portions, after a period of time are unable to re-acquire their normally elastic character. The new cover must be made, the filling suitably placed and the front and back portions of the cover must be quilted or knotted through the filling material.

This invention provides an entirely new type of comforter, in which the down or other filler is carried in an absolutely free state in a parallel series of socks which are formed of an extremely closely woven, down-impermeable material which is also very light in weight.

No quilting or knotting is employed in this invention, therefore the filler is free to retain and to restore its elasticity. No portion of the filling material is ever secured in a compressed condition. The socks are made sufficiently small in cross-section to function as a retainer for the filler.

The cover is made with a series of pockets to receive the socks of filler, and the unit is closed by means of a "Zipper," therefore the covers are easily and quickly removed for cleaning or for mere interchange of covers to fit in with predetermined arrangements, color schemes or ensembles. The socks with filler are easily and conveniently subjected to sunning, dusting or fumigating operations, therefore the arrangement is ideal so far as adaptability, convenience,

comfort, interchangeability and cleanliness are concerned.

The objects and advantages of the invention reside in:

5 First; a comforter in which the covering material is quickly and conveniently removable for washing or otherwise cleaning, or for interchange with a cover of different pattern or color scheme.

10 Second; a comforter in which the filling material is free of restricting or compressive influences, such as quilting or knotting, whereby the filling material is at all times free to retain or to restore its original resiliency and fluffiness.

15 Third; a comforter in which the filling material is freely disposed in sleeves of light weight material which is also impervious to the filling material, and which sleeves of filler are easily inserted into pockets formed in a cover member.

20 Fourth; a comforter in which the filling material is freely disposed in sleeves of lightweight material as outlined, and in which the sleeves are provided with elements at one end for cooperation with the fingers of a hand or with a plunger for advancing the sleeves of filler into the pockets, and in which the other ends of the sleeves are tied together in a continuous series of parallel sleeves.

25 Fifth; a comforter in which a cover element is provided for a multiplicity of filler-filled sleeves, and with means for maintaining suitable spacing between the sleeves, and in which a tuck strip is provided at the foot end of the cover and which is free of filling material to provide a non-bulging foot tuck member for a bed.

30 Sixth; a comforter as outlined in which the connections between the pockets for the sleeves form non-resistive hinge elements, to eliminate the crawling and slipping tendency which is prevalent in conventional comforters and to insure close cooperation of the comforter with the body of the sleeper.

35 In describing the invention reference will be made to the accompanying drawing in which:

Fig. 1 is a plan view of the underside of the invention and showing the "Zipper" closure for the pockets.

40 Fig. 2 is a fragmentary view of the filler carrying structure and illustrating the series of parallel sleeves.

45 Fig. 3 is an enlarged section taken on line 3—3 of Fig. 2.

50 Fig. 4 is an enlarged section taken on line 4—4 of Fig. 2, modified to show the sock-insert-

ing plunger in place and which plunger is used to insert the filler socks in the cover pockets.

Fig. 5 is a diagrammatic view showing the hinging and body contour-conforming characteristics of the invention.

Fig. 6 is an enlarged sectional view showing the complete cross-sectional structure of the cover, sock, and filler combination.

The invention consists of a comforter which includes a filler structure and a removable and replaceable cover structure.

The filler structure consists of a series of parallel socks or sleeves 10 which are made of a down-impervious, lightweight material; each sleeve being preferably equal in length to the comforter and being comparatively small in cross-section when filled, and being closed all around as by sewing 11; one end 12 of the sleeves being free of each other, and the other end 13 being attached to a suitable connecting element, such as a tape 14, which tape maintains the correct spacing and relation between the respective sleeves of the series. This tape also facilitates handling of the filler structure as a whole, for airing, sunning, or cleaning; the separated sleeves being effective in increasing the sunning and airing efficiency.

The filler 15 is blown into the sleeves and left completely free; no stitching, quilting or knotting being resorted to, therefore the filler, such as down, kapok or wool is entirely free to retain or to restore its resiliency and fluffiness, and the maximum degree of heat insulating efficiency is thus assured. The comparatively small cross-sectional area of the sleeves insures the maintenance of uniform distribution.

At the free end of each sleeve a pocket 16 is formed to receive the fingers or a plunger 17 such as a broom handle or like suitable element by means of which the sleeves can be individually inserted in the cover pockets.

The cover consists of a top or uppersurface element 18 and a bottom or undersurface element 19 which are made of any desired material such as silk, rayon, or cotton materials and of any desired color combination.

The top and bottom elements 18 and 19 are stitched together from the head end 20 to the foot end 21, as indicated at 22 to form a series of pockets 23 with the stitched portions 22 forming non-resistive hinges between the pockets. The pockets 23 are made of a suitable size to quite snugly receive the sleeves of filler material, the sleeves being substantially equal in length to the pockets.

The foot end of the upper surface element 18 of the cover extends beyond the foot end of the undersurface element 19 to form a tuck strip 24 to be tucked under the foot end of a mattress (not shown), and the foot end of the undersurface element 19 is releasably attached to the upper surface element by any suitable means such as by means of the "Zipper" 25.

For cleaning or for changing covers, it is merely necessary to slide the runner 26 of the "Zipper" to open the foot end of the cover, after which the filler structure is easily withdrawn from the pockets. The filler structure can be hung on a line for airing or sunning by clothes-pinning the tapered ends of the structure to the line.

To assemble the sleeve and filler structure in a cover, the sleeves are taken in series and inserted into the respective pockets in the cover, either by inserting the ends of the fingers of the hand (not shown) or a plunger 17 into the pocket 75

16 and pushing the end of the sleeve to the head end of the cover or bottom of the pocket 23, and after all of the sleeves are inserted, the runner 26 is slid back to secure the top and bottom elements of the cover together.

When the structure is assembled, the various sections of the comforter tend to fold one over the other rather than to create an urge to cause the comforter to gradually creep or slide off the bed. This effect is due to the unrestricted hinging action along the seams 22, and due to this same effect, the comforter very closely conforms to the body of the sleeper, thus assuring a maximum of comfort and warmth.

It will be noted that a number of interchangeable covers may be provided for a single filler structure, particularly for sanitary purposes in hotels, hospitals, and similar institutions; and also for the purpose of beautifying bedrooms, for carrying out defined color schemes or for matching different drapes or ensembles.

Obviously it would be possible to make the filler structure in various ways, such as in two units in which one unit would be inserted from the foot end and the other from the head end, which modifications are not shown; and there are also other modifications possible, and it is therefore understood that variations in construction and arrangement of parts, which variations are consistent with the appended claims may be resorted to without detracting from the spirit or scope of the invention or sacrificing any of the advantages thereof.

We claim:

1. A comforter comprising a series of filler elements and a cover having a series of parallel pockets with the series extending throughout the width of the cover and with the respective filler elements removably disposed in the respective pockets; and in which said filler elements each consist of a down-impervious sleeve filled with filler material, with one end of the filler elements being free of each other for separate insertion in said pockets and with the other ends attached to a common connection for maintaining the spacing and relation of the respective elements of the series, and in which the attachment of the other ends maintains said other ends from slipping down inside the pockets through cooperation of the common connection with the ends of the pockets.

2. A comforter comprising a series of filler elements and a cover having a series of parallel pockets with the series extending throughout the width of the cover and with the respective filler elements removably disposed in the respective pockets; and in which said cover element consists of an uppersurface element and a lower-surface element longitudinally divided to form said series of pockets by spaced attachment of the two elements, with said pockets closed at one end and releasably closed at the other end, for convenient removal and insertion of the filler elements therein and their retention of said filler elements, and in which said filler elements are all connected together at one end to maintain the elements in their respective positions, and with the connections between the elements cooperating with one end of the spaced attachments to maintain said elements against working down into the pockets.

3. A comforter comprising a cover element having a head end and a foot end and uppersurface and undersurface elements; a series of parallel pockets formed between said uppersurface and

undersurface elements by continuous connection between the upper surface and undersurface elements with each pocket extending from said head end to said foot end; and filler elements connected together at one end and individually fitting in said pockets and extending throughout the lengths thereof, the connections between said elements maintaining said elements against working down into said pockets through cooperation of the connections between the elements with the terminals of the continuous connections forming the pockets; and means for releasably closing said pockets to retain said filler elements and tie the bottoms of the uppersurface and undersurface elements together, and to permit convenient interchange of cover elements.

4. A comforter comprising parallel pockets and removable filler elements, in which each of said filler elements consist of a down-impervious sock filled with suitable filler, with one end of the respective socks free of each other and the other ends tied together in parallel arrangement with a common connecting element maintaining the spacing and relation of the various socks and for cooperation with one end of the pockets to maintain the socks against working down into the pockets.

5. In a comforter having a series of parallel pockets formed throughout the length thereof by attachment of the upper and under cover elements of the cover; filler elements comprising socks filled with a filler material and having a common connection connecting all of the filler elements together at one end with the common

connection forming retaining means in cooperation with the attachments forming the pockets to maintain said one end of the respective filler elements from working down into the pockets, and to maintain said one end of the respective filler elements in relative position against twisting and bunching within the pockets.

6. A structure as defined in claim 5; and a rod pocket formed at the other end of each sock for insertion of a rod for forcing the other end of each sock down to the bottom of the pocket; said common connection between the socks coincidentally functioning to maintain said socks in relative order and for convenience in hanging the entire series of socks for airing and to form the entire series into a single unit to prevent misplacement or loss.

7. A comforter having a series of parallel pockets formed throughout one dimension thereof by attachment of the upper and under cover elements of the cover; filler elements removably disposed in said pockets; releasable closing means for at least one end of said series of pockets to provide access to the pockets at will for insertion and removal of said filler elements and a common connection connecting all of the filler elements at one end in slightly spaced relation for cooperation of the common connection with the attachments which form the pockets, to maintain the filler elements from creeping down into the pockets.
